CLAIM

The ornamental design for a stylus pen clip, as shown and described.

DESCRIPTION

FIG. 1 is a front bottom side perspective view of the stylus pen clip showing my new design;

FIG. 2 is a front elevational view thereof;

FIG. 3 is a right side view thereof which is a mirror image of the left side thereof;

FIG. 4 is a back elevational view thereof;

FIG. 5 is a bottom plan view thereof; and,

FIG. 6 is a top plan view thereof.

The broken lines depicting environmental structure are for illustrative purposes only and form no part of the claimed design.
